US0D1046670S

(12) **United States Design Patent** (10) **Patent No.:** **US D1,046,670 S**
(45) **Date of Patent:** **** Oct. 15, 2024**

(54) **DIGITAL CANISTER GAUGE**

(71) Applicant: **WORTHINGTON CYLINDERS CORPORATION**, Columbus, OH (US)

(72) Inventors: **Louis Farchione**, Columbus, OH (US);
Joel Vangilder, Columbus, OH (US);
Brian Poland, Columbus, OH (US)

(73) Assignee: **Worthington Cylinders Corporation**,
Columbus, OH (US)

(**) Term: **15 Years**

(21) Appl. No.: **29/873,768**

(22) Filed: **Apr. 7, 2023**

Related U.S. Application Data

(63) Continuation of application No. 29/747,756, filed on Aug. 25, 2020, now Pat. No. Des. 986,752.

(57) **CLAIM**

The ornamental design for a digital canister gauge, as shown and described.

DESCRIPTION

FIG. 1 is a top perspective view of a digital canister gauge showing our new design;

FIG. 2 is a bottom perspective view of the digital canister gauge illustrated in FIG. 1;

FIG. 3 is a right side view of the digital canister gauge illustrated in FIG. 1;

FIG. 4 is a front view of the digital canister gauge illustrated in FIG. 1;

FIG. 5 is a left side view of the digital canister gauge illustrated in FIG. 1;

FIG. 6 is a rear view of the digital canister gauge illustrated in FIG. 1;

FIG. 7 is a top view of the digital canister gauge illustrated in FIG. 1; and,

FIG. 8 is a bottom view of the digital canister gauge illustrated in FIG. 1.

The broken lines show portions of the design that form no part of the claimed design.
